CLAIM

The ornamental design for an illuminated control device, as shown and described.

DESCRIPTION

FIG. 1 is a front perspective view for an illuminated control device showing a first state in a sequence showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 shows a second state thereof;

FIG. 8 shows a third state thereof;

FIG. 9 shows a fourth state thereof;

FIG. 10 shows a fifth state thereof;

FIG. 11 shows a sixth state thereof;

FIG. 12 shows a first state in a sequence comprising a second embodiment thereof;

FIG. 13 shows a second state thereof;

FIG. 14 shows a third state thereof;

FIG. 15 shows a fourth state thereof;

FIG. 16 shows a fifth state thereof; and,

FIG. 17 shows a sixth state thereof.

The gray shaded elements represent illumination.

The dashed broken lines represent structure or features which form no part of the claimed design; the broken lines themselves form no part of the claimed design.

In each of the embodiments, the claimed design sequentially transitions from the first state to the last state in the sequence. The period with which one image transitions to another image forms no part of the claimed design.
